UNITED STATES PATENT OFFICE.

KATIE R. STONE, OF SAUNDERSVILLE, MASSACHUSETTS.

DESIGN FOR A PACKAGE-SUPPORTING CLIP FOR BICYCLES

SPECIFICATION forming part of Design No. 29,110, dated July 26, 1898.

Application filed April 29, 1898. Serial No. 679,249. Term of patent 7 years.

To all whom it may concern:

Be it known that I, KATIE R. STONE, a citizen of the United States, residing at Saunderville, in the county of Worcester and State of Massachusetts, have invented a new and useful Design for a Package-Clip for Bicycles, of which the following is a specification.

My invention relates to a substantially S-shaped package-supporting clip for bicycles, comprising a handle-bar-engaging section and a package-wrapping string-receiving section.

The essential features of my design as hereinafter set forth are illustrated in the accompanying drawings, in which—

Figure 1 is a perspective view of a package-carrying clip constructed according to my invention, and Fig. 2 is a side elevation of a package-carrying clip embodying my design.

Referring to the drawings and in detail, my design for the somewhat S-shaped package-carrying clip A comprises the handle-bar-engaging section 10 and the reversely-curved section 11.

Having described my invention, what I claim as new, and desire to secure by Letters Patent of the United States, is—

The design for a package-supporting clip for bicycles, substantially as herein shown and described.

In testimony whereof I have hereunto set my hand in the presence of two subscribing witnesses.

KATIE R. STONE.

Witnesses:

FREDERICK B. HARLOW,
PHILIP W. SOUTHGATE.
